JOHN F. KELLY, OF PITTSFIELD, MASSACHUSETTS.

MAGNET-GROUPING DEVICE FOR ELECTRICAL MUSICAL INSTRUMENTS.

1,256,804.

Specification of Letters Patent. Patented Feb. 19, 1918.

Continuation of application Serial No. 722,118, filed September 24, 1912. This application filed June 4, 1914. Serial No. 842,989.

To all whom it may concern:

Be it known that I, JOHN F. KELLY, a citizen of the United States of America, residing at Pittsfield, in the county of Berkshire and State of Massachusetts, have invented certain new and useful Improvements in Magnet-Grouping Devices for Electrical Musical Instruments, of which the following is a specification.

10 This invention relates to improvements in magnet grouping devices for electrical musical instruments of the type in which a perforated note or music sheet is employed to control the operation of the electro-magnets of the instrument which, in turn, operate the keys or other devices which cause the tone-producing devices to operate, the present case being a continuation in part of my allowed application, Ser. No. 722,118, filed 15 Sept. 24, 1912.

An object of the present invention is to provide devices by means of which the total number of circuit closers or circuit-controlling devices of the instrument may be reduced, or, what amounts to the same thing, 20 reducing the number of longitudinal rows of slots or perforations in the note-sheet of a music roll. On the key-board, for instance, on an eighty-eight note piano, the width of 25 the note-sheet is objectionable on account of the expense in making it, especially if composed of heavy and expensive material.

A further object of the present invention is in the provision of devices or means by 30 which the length of the perforations in the note-sheet which control the circuit closers of the note-name group may be reduced. By reason of the fact that the perforations in the note-sheet, which controls the operation 35 of the circuit closing devices in the note-name group, occur more frequently than the perforations which cause the individual notes of the instrument to be played, it is desirable that some means be provided 40 to cut down or lessen the length of these perforations in order to avoid the objection of unduly weakening the note-sheet.

A further object of the invention is in the provision of devices to cause the key-operating electro-magnets to automatically 45 retain their own circuit closed until the termination of the sounding of the tone or note is due. This closure must, therefore, continue or be maintained until after the note-name group of circuit controllers have

ceased to operate after first closing the circuit to the key-operating magnets, as will be explained in the body of the specification.

I employ a separate or independent connection from one terminal of each of the 60 operating magnets to a common circuit closer, and on the other side or terminal of the operating magnets there is a branch grouping of one or two of these operating magnets of different note-name. In order 65 to operate a key-operating magnet for causing a note to be sounded, a contact in the circuit of the note-name or larger group is closed, and in this circuit is included the contact corresponding to the smaller grouping. 70 This arrangement or scheme of grouping over the piano scale, as will be fully explained in the body of the specification, cuts out thirty-six of the sharps, and, at the same time, only adds twelve contacts in the larger 75 or note-name group, thus effecting a saving over the entire scale of twenty-four contacts. Consequently a less number of perforations in the note-sheet is required and therefore a corresponding saving in width in material 80 and expense. This arrangement or scheme of connecting the operating magnets by grouping them together with separate lines to a common contact prevents the possibility of any cross-connections between the operating magnets and, at the same time, saves electrical energy, on account of the reduction 85 in length of the perforations which control the circuit closers of the note-name group. 90

Referring to the drawings—

Figure 1 is a diagrammatic view of the electrical connections for the groupings showing the separate lines leading to a common circuit closer of the note-name group, also 95 showing the devices to maintain the circuits to the operating magnets of different note-name closed until the termination of the note being played is properly due.

Fig. 2 is a view showing the devices for 100 closing and automatically holding the circuit closed to each key-operating magnet while the note is being played or until the termination of the note being played is due.

Fig. 3 is a detail view showing the arrangement and relative size of the slots in the note-sheet with the two sets of perforations, the smaller ones for controlling the operation of the note-name group and the larger ones for controlling the operation of 110

the individual notes, and, Fig. 4 is a detail view illustrating in cross section the tracker-bar and note sheet.

Referring to the drawings in detail, 1, 2, 5 and 3 may be considered as designating the groups of key or other operating magnets which operate the keys of the instrument that cause tones of different note-names to be sounded. In group 1, for instance, the 10 magnets 6 of each of the groups designated 1 may be considered as connected to the keys which effect the sounding of the "a" note. The magnets 7 of each of the groups designated 1 may be considered as connected to 15 the keys of the instrument which operate the "a" sharp note. The magnets 8 of each of the single groups indicated at 2 may be considered as being connected to the keys of the instrument which causes the note "b" to be 20 sounded. The magnets 9 may be considered as connected to the keys which operate the "c" note, and the magnets 10 the "c" sharp notes.

Extending from one terminal of each of 25 the key-operating magnets of the several groups indicated at 1, 2, 3, are wires 11, 12, and 13 which terminate at a common relay or circuit-closing device 14, the movement of the pivoted armature 15 of which simultaneously closes the circuit to each of the 30 wires 11, 12, and 13, the pivot being indicated at 15'. This closure may be accomplished by providing the pivotally mounted armature 15 with an extension piece or finger 35 16. The larger group of circuit closing devices is designated as a whole by the numeral 17. This group may be termed the note-name group. The operating magnets 7 of each of the groups 1, representing the "a" 40 sharp notes, each have a separate connection 18, 19, and 20, which extends to a common relay or circuit closing device 21. In the same manner, a separate connection extends from one terminal of each of the operating 45 magnets to a common circuit closing device or relay indicated at 14, 21 and 29. The opposite terminals of the key-operating magnets 6 and 7, for instance, of the group designated 1 are connected together at the point 50 22 to a common wire 23 which leads to a circuit-controlling or closing device 24, which comprises a perforation in the note-sheet 25 that represents the note that is to be played or sounded.

55 As the note sheet 25 moves over the tracker bar 33', see Fig. 4, the terminals 23, 30, etc., enter the openings 24 in the tracker bar and closes contact with the conductor 34' which extends through the bar and is electrically 60 connected to the wire 33 which extends to the source of electrical energy.

The wires 26, 27, and 28 separately extend from one terminal of each of the magnets 8 of the "b" natural group to a common circuit closer 29. In order to avoid confusion,

the opposite terminals of these magnets are not grouped with any of the other operating magnets but are connected by means of a wire 30 directly with a perforation 24 of the note-sheet which represents the "b" natural note in that particular octave.

The battery or other source of electrical energy is indicated at 31, one terminal of which is connected by a wire 32 to a wire 33 which may be considered the tracker-bar terminal of the instrument and also the common connection from one terminal of the battery to the branches 23, 30, etc., which serves to connect operating magnets of different note-names together. The note-sheet 25 effects 80 the closure of the various circuits in the two sets of groupings of electro-magnets, that is to say, the note-name group 17 of the same name and the key-operating group 1, 2, 3, etc., of different note-name. Connected to 85 the other terminal of the battery is a return wire 34. 35 designates fixed contacts that are connected to the return wire 34 by means of the wires 36 and 37. Connected to the tracker-bar or terminal 33 are wires 38 which 90 serve to close the circuit to any one of the electro-magnets or relays 14, 21, 29, etc., by means of the wires 39 which coöperate with the short perforations 40 in the note-sheet 25. The other terminals of the electro-magnets 95 14, 21, 29, etc., are connected by means of the wires 41 with the wire 37 and this, in turn, to the wire 36 that is connected to the wire 34 that leads to the other terminal of the battery.

Referring now to the devices by means of which each of the circuits to the individual key-operating magnets is automatically maintained closed until the termination of the sounding of the note is due. 42 is an 105 oscillating armature which is connected to the key 43 of the instrument by means of the rod 44. Secured to this armature is an eccentric or cam 45. Attached to a suitable support, adjacent to the poles of the magnets and insulated therefrom and from each other, are the contacts 46 and 47. These are connected by means of the wires 48 and 49 to the wires 37, 11, 18, 26, etc., of each group. That is to say the switch 46 and 47 is located 110 in wires 48 and 49 which are in a shunt circuit parallel to the wires 11, to which the contact 15' is connected. This short circuits the switch 15, 16.

It is further to be understood that the 120 switch 46 and 47 is used on each of the operating magnets in the different groups 1, 2, 3, etc., and that the switch for each operating magnet is connected in the same manner to the various wires, 18, 26, etc. A portion of the perforated note-sheet is indicated in Fig. 3 in which the length of the perforation 24 indicates the time that the note represented thereby is to be played during the movement of the note-sheet over the tracker-bar. The 130

perforations 40 which are shorter in length are used simply to close the circuit through the relay magnets 14, 21, 29, etc., and, as stated, by making them short the sheet is not 5 weakened. It is evident that in order to cause a note to be sounded that two of the perforations 24 and 40 must simultaneously coöperate.

The operation of the apparatus is as follows—First, consider that one of the perforations 40 in the note-sheet 25 closes the circuit from one terminal of the battery 31 to the wires 32, 33, 38, perforation 40, and wire 39 to one of the electro-magnets, say 14, depending, of course, upon which one of the perforations is brought into registration with the terminals of the wires 38 and 39. The current then flows to the other terminal of the battery by the wires 41, 37, 36, and 34 20 back to the other terminal of the battery. At the same time, one of the perforations 24, representing a note to be sounded, in the group 1, for example, of the key-operating electro-magnets will close the circuit through 25 the magnet 6, for example, permitting the current to now flow from the battery 31, wire 32, tracker-bar terminal 33, perforation 24, wire 23, to the key-operating electro-magnet 6, for example, wire 11, contact 16, armature 30 15, contact 15', wires 35, 37, 36, and 34 to the other terminal of the battery 31. In the meantime, the oscillating armature 42, by means of the eccentric or cam 45, has now closed the contacts 46 and 47. During this 35 interval, the short perforations 40 have passed from the terminal wires 38 and 39, but the circuit from the battery is still closed in order to cause the note represented by the perforation 24 to be sounded as long as the 40 perforation 24 registers with the wire 23 and perforation 24 of the tracker-bar terminal 33. The current now flows from the battery 31 by means of the wires 32 and 33, perforation 24, wire 23, the key-operating 45 electro-magnet 6, for example, contacts 46 and 47, wires 37 and 36, back to the other terminal of the battery. Or to state the matter more clearly, it will be seen that the key-actuating magnets will retain their own 50 circuit closed as long as the perforation 24 is in use. Each of the relays or electro-magnets 14, 21, and 29 serves merely to close the circuit through the particular key-operating magnets which, in turn, close the contacts 55 15', for example.

By means of this arrangement or double grouping of the contacts, it will be seen that the number of perforations in the note-sheet is materially reduced. The number of contacts in the terminals 38 and 39 which corresponds with the number of perforations 40 in the note-sheet in the note-name group 60 17 will, of course, be 12, namely, from "a" to "g" sharp. By combining the naturals 65 with the sharps in the smaller groups 1, 2,

3, etc., as "a" and "a" sharp and connecting the two wires 11 and 18 on one side or terminal of the key-operating magnets 6 and 7, as shown at 22, with a common wire 23, a single circuit-closing perforation 24 in the 70 note-sheet will serve to operate either one of the key-operating magnets that effect the sounding of these two notes. This manner of connecting or grouping all of the notes with their sharps, as "a" and "a" sharp, over 75 the whole key-bar makes 36 groups each of which contains two key-operating magnets, but from this number must be deducted the number twelve given above which is the number of contacts in the note-name group 80 17. Therefore, the total number of contacts over the whole range of the key-board is reduced by 24. The same grouping can, of course, be made by making a similar group of flats and naturals instead of sharps and 85 naturals, and a still greater saving of space on the note-sheet can be effected by taking the notes in pairs along the scale, but this would be apt to be confusing to the operator when laying out the master-roll. 90

It is to be understood that the present improvement is not limited to the actuation of the keys as the actuating devices may be directly connected to the action or the devices which cause the tone sounding devices to 95 operate, and it is also obvious that an analogous method such as herein described could be employed embodying the same general principle to operate pneumatic players if so desired. 100

It will be seen that each one of the operating magnets of a group, as 1, is separately connected to a different relay, and, by reason of this fact, there would not be any danger of any of the other operating magnets being 105 accidentally sounded on account of cross connections between these magnets.

By the terms "tone-producing devices" or "sound-producing devices" wherever used in the specification, it is to be understood to 110 refer to the part of the musical instrument which actually emits or produces the musical sounds or tones as, for example, the tuned wires of a piano.

Also, wherever the terms "circuit closer" 115 or "circuit controller" is used, it is to be understood as referring to a make-and-break device and not to the perforated note-sheet which may be said to "control" the circuit.

The term "tracker-bar" is understood as 120 referring to the element over which the note-sheet is drawn during the operation of the instrument.

It is also to be understood that the "operating magnets" are to be considered as 125 being connected into two groups, as, for example, magnets 6 and 7 in all of the octaves constitute one group, magnets 8 or the "b" natural of each octave another group; and that the operating magnets may, therefore, 130

be considered as having a double arrangement of grouping.

What I claim is—

1. An electrically-operated musical instrument, comprising in combination, connections in parallel on one side of the operating magnets to group together said magnets which operate the tone sounding devices of the same note-name, a common connection, 5 connections extending from the other terminals of said magnets to the common connection to group together in pairs to the common connection some of said magnets which operate the tone sounding devices of different note-names, a source of electrical energy to the opposite terminals of which said parallel and group connections are connected, a tracker-bar in said latter connections, and a note-sheet coöperating with the tracker bar 10 for controlling the parallel and group connections.

2. An electrically operated musical instrument, comprising, in combination, electro-magnets to operate the tone producing devices, connections to group together one terminal of each of said magnets for causing the production of tones of the same note-name, a circuit closer in each of said connections, a source of electrical energy, connections from the other terminal of each of said magnets to a terminal of the source of electrical energy, a circuit controller in each of said last mentioned connections, some of the latter connections serving to connect together magnets which operate tone-producing devices of different note-names, and connections from the other terminal of the source of energy to the first-mentioned connections, a tracker bar in said connections, 25 and a note sheet coöperating with the bar for controlling the connections.

3. An electrically operated musical instrument, comprising in combination, operating magnets, connections from one terminal of each of said magnets for grouping said magnets together which operate tone-producing devices of the same note-name, circuit closers for said connections, a source of electrical energy, one terminal of which is 45 connected to said connections, a plurality of said magnets each having its other terminal connected to a separate connection, a tracker-bar, terminals therein to which each of the last named connections is connected, and 50 connections from the terminals of the tracker-bar to the other terminal of the source of electrical energy, said tracker-bar having a less number of terminals than the number of operating magnets, whereby a 55 note-sheet formed with a number of perforations that is less than the number of tone sounding devices may be used to control the operation of all of the operating magnets.

4. An electrically operated musical instrument, comprising in combination, electro-

magnetic operating devices for operating the sound producing devices, a source of electrical energy, connections from one terminal of each of said operating devices to the source for grouping said devices together which 70 produce tones of the same note-name, a contact in each of said connections, an electro-magnet to operate each of said contacts, connections from the source to one terminal of each of the contact operating electro-magnets, connections from the other terminal of the contact operating electro-magnets to the other terminal of the source, connections from the opposite terminal of each of said first named operating devices to the source 80 for grouping a plurality of the electro-magnetic operating devices together which operate tone producing devices of different note-name, a tracker-bar having the terminals therein included in the last mentioned 85 connections, the number of terminals in the tracker-bar being less than the number of tone - producing devices, and a perforated note-sheet to engage the tracker-bar as described. 90

5. In an electrically operated musical instrument, the combination, of electro-magnets, armatures therefor, connecting means between the armatures and the tone producing devices for operating the tone-producing 95 devices, a source of electrical energy, connections from the terminals of the magnets to the terminals of the source of energy, a circuit closing device in each of said connections, means for operating said closing device in each connection, and means operated by the electro-magnets for maintaining the circuit closing devices in said connections closed during the periods which correspond with the notes of different length, as described. 100

6. In an electrically operated musical instrument, the combination, of electro-magnets, armatures operated thereby for operating the tone-producing devices of the instrument, a source of electrical energy, independent connections from the terminals of said magnets to the terminals of the source of energy to group said magnets together which produce tones of the same note name, 110 a circuit closing device in each of said connections, the circuit closing devices in said connections being operated by the movements of the armatures of the electro-magnets for maintaining the circuit closed to 115 that particular electro-magnet during the operation of the tone producing device. 120

7. In an electrically-operated musical instrument, the combination, of operating magnets for actuating the tone producing 125 devices of the instrument, a source of electrical energy, means extending from one terminal of the source of electrical energy to electrically connect the operating magnets together which operate tone-producing de- 130

- 5 vices of the same note-name, a circuit closer in each of said connecting means, an electro-magnet to operate the circuit closer, separate means to electrically connect together some 5 of the operating magnets which actuate tone-producing devices of different note-name, a common terminal to which the last-mentioned connecting means is connected, a tracker-bar to which the common terminals 10 are connected, a make-and-break device in said last named connection for controlling the operating magnets, the number of terminals in the tracker bar being less than the number of operating magnets, whereby a 15 note-sheet having a number of longitudinal rows of perforations that is less than the number of operating magnets may be used to control the operation of all of the tone producing devices of the instrument, as described. 20
8. In an electrically operated musical instrument, the combination, of operating magnets, connections from one terminal of said magnets to group together said magnets 25 which operate tone-producing devices of the same note-name, a circuit closer in each of said connections, means controlled by the note-sheet to operate the circuit closers, connections from the opposite terminals of each 30 of the operating magnets to group together some of the operating magnets which operate tone-producing devices of different note-names, a connection from one terminal of each of the magnets to the source of electrical 35 energy, a circuit closer in the last named connection and independently operated by each individual operating magnet for holding the circuit closed through that particular operating magnet for a time correspond- 40 ing with the length of perforation in the note-sheet which represents the time the note is to be played, a source of electrical energy, a tracker-bar, terminals therein to which the connections from the opposite ter- 45 minals of the operating magnets extend and connections from the tracker-bar terminals to the terminals of the source of electrical energy, the number of terminals in the tracker-bar being less than the number of 50 operating magnets.
9. In an electrically operated musical instrument, the combination, of operating magnets, electro-magnetic make-and-break devices, connections extending from the ter- 55 minals at one end of said magnets to the make-and-break devices for grouping those magnets together which cause the production of tones of the same note-name, a source of electrical energy, connections from the 60 source to the terminals of the said make-and-break devices, connections extending from some of the opposite terminals of said magnets to the source for grouping together the operating magnets which cause the produc- 65 tion of tones of different note-names, a
- tracker-bar, terminals therein and connected to the last named connections, and means including a perforated note-sheet coöperating with the terminals in the tracker-bar and the last named connections for opening and closing the connections to said make-and-break devices, and for opening and closing the connections from the opposite terminals of said magnets which connect together operating magnets of different note names. 70
10. In a musical instrument, the combination, of operating devices, a source of electrical energy, means to group said devices together which cause the production of tones of the same note-name, means to group together a plurality of said devices which cause the production of tones of different note-names, means including a tracker-bar and note-sheet for controlling the operation of said grouping means for energizing any 80 individual operating device, as described. 85
11. In a musical instrument, the combination of electromagnetic operating devices, a source of electrical energy, a perforated note-sheet controlling said devices, connect- 90 ing means from the terminals on one side of said operating devices to one terminal of the source of energy for grouping together said devices which cause the production of tones of the same note name, connections on the 95 other side of some of said devices to the other terminal of the source of energy for grouping together devices which cause the production of tones of different note names, a common connection from one terminal of 100 the source of energy, a branch connection from each of the first mentioned terminals on one side of said operating means to the common connection, a make and break device in each one of said branches controlled 105 by the note-sheet.
12. In an electrically operated musical instrument, electro-magnets, armatures therefor, connecting devices from the armatures for actuating the sound-producing devices 110 of the instrument, a source of electrical energy, connections therefrom to the terminals of the electro-magnets, make-and-break devices in said connections, connections from each of the same terminals of the electro- 115 magnets to the source of electrical energy, a make-and-break device in each of the last named connections, means operated by the movements of the armatures to operate the make-and-break devices in said last-named 120 connections, connections extending from each of the other terminals of the electro-magnets to the source of electrical energy, a tracker bar in the connections, and a perforated note-sheet coöperating with the 125 tracker-bar for controlling the operation of all of the make-and-break devices.
13. An electrically-operated musical instrument, comprising, in combination, operating magnets, connections from one side 130

of all of the magnets to group said magnets together which operate tone-sounding devices of the same note-name, connections from the other side of some of the magnets 5 to connect a plurality of said magnets together which operate tone-sounding devices of different note-name, circuit closers in all of said connections, a single source of electrical energy, and to which the connections 10 are connected.

14. An electrically-operated musical instrument comprising, in combination, electro-magnetic devices for operating the sound-producing means, a source of electrical energy, connections from one terminal of each of said devices to the source of electrical energy for grouping said devices together which produce tones of the same note-name, a contact in each connection, an electro-magnet 15 to operate each contact, a tracker-bar, terminals therein, a connection from one terminal of each of the contact operating electro-magnets to separate terminals in the tracker-bar, a connection from 20 the terminals of the tracker-bar to the source of electrical energy, a connection from the other terminal of each of the contact operating electro-magnets to the other terminal of the source of electrical energy, 25 connections from some of the opposite terminals of said operating devices to terminals in the tracker-bar for grouping a plurality of electro-magnetic devices together which operate the sounding devices of different note-name, a connection from said 30 last mentioned terminals to the source of energy, said tracker-bar having a less number of terminals therein than the number of said sound producing devices, a note-sheet engaging 35 the tracker-bar for closing the terminal connections therein, whereby the connections to said sound producing devices may be operated.

15. In an electrically operated musical instrument, the combination, of operating magnets, a single source of electrical energy, connections extending from the terminals of said magnets to the terminals of the source of electrical energy for electrically connecting said magnets together into 45 a double grouping arrangement, a circuit closer comprising a note-sheet in the connection of each group, one of said grouping connections serving to sound tones of the same note name and the other grouping connections 50 serving to sound tones of different note-names, as described.

16. In an electrically-operated musical instrument, the combination, of operating magnets, armatures therefor, connecting means from the armatures for operating the sound producing means of the instrument, a source of electrical energy, connections extending from the terminals of each of the 60 operating magnets to a terminal of the

source for grouping said magnets which operate the tone sounding devices of the same note-name, make-and-break devices in the connections, connections from the other terminals of the operating magnets to the other 70 terminal of the source grouping said magnets together which operate tone sounding devices of different note-name, a tracker-bar, terminal therein and included in the connections and a perforated note-sheet engaging 75 the tracker-bar and coöperating with the terminals for causing the closure of the connections from the source of electrical energy to the operating magnets.

17. An electrically-operated musical instrument comprising in combination, a source of electrical energy, electro-magnetic actuating devices which operate the tone-producing devices, connections from one terminal of each of said actuating devices to 80 the source electrically connecting said actuating devices together which sound tones of the same note-name, circuit closers for the connections, connections from some of the other terminals of said devices to the source 85 electrically connecting some of said devices together which sound tones of different note-name, a tracker bar and note sheet interposed in said last-named connections to control the operation of said devices, and means 90 controlled by the tracker bar and note sheet 95 controlling the circuit closers for the first mentioned connections.

18. An electrically-operated musical instrument, comprising, in combination, electro-magnets to operate the tone-sounding devices, a single source of electrical energy, connections extending from one of the terminals of the electro-magnets to the source 100 of electrical energy to group together said 105 magnets which sound tones of the same note-name, circuit closers in said connections, connections extending from some of the other terminals of said magnets to the other terminal of the source of electrical energy, 110 circuit closers in said latter connections, the latter connections serving to group together said electro-magnets which sound tones of different note-name.

19. An electrically-operated musical instrument comprising in combination, a source of electrical energy, operating magnets, connections from one of the terminals of each of said magnets to a terminal of the source of electrical energy for grouping the 115 same together which operate tone-sounding devices of the same note-name, circuit closers in said connections, a plurality of said magnets having their other terminals connected for grouping said last mentioned 120 magnets together which operate tone-sounding devices of different note-name, circuit closers in said last mentioned connections, a tracker bar having terminals therein of less 125 number than the number of tone-sounding 130

devices of the instrument, some of said terminals in the tracker bar being connected to the connections extending from said other terminals, and other connections from the 5 terminals in the tracker bar extending to the other terminal of the source of electrical energy.

20. An electrically-operated musical instrument, comprising in combination, elec- 10 tro-magnetic devices to operate the sound producing means, a source of electrical energy, connections from one terminal of each of said devices to one terminal of the source for grouping said devices together which 15 produce tones of the same note-name, a contact in each of said connections, electro-magnets to operate the contacts and connections therefrom to the source of electrical energy, a tracker bar, terminals therein, a connec- 20 tion from the source to the terminals of the tracker bar, connections from some of the opposite terminals of said operating devices to the tracker bar for grouping said devices together which produce tones of different 25 note-name, the tracker bar having a less number of terminals than the number of the

sound producing devices, and a note sheet to engage the tracker-bar for closing the circuits to said operating devices and to the contact operating electro-magnets. 30

21. An electrically-operated musical instrument, comprising, in combination, operating magnets, connections from one side of the magnets to group together said magnets which operate tone-sounding devices of 35 the same note-name, connections from the other side of the magnets to group together a plurality of said magnets which operate tone-sounding devices of different note-name, circuit closers in said connections, a 40 source of electrical energy to which said connections are connected, a tracker bar, terminals therein which are included in the connections from said other side of the magnets and a note sheet coöperating with the 45 tracker-bar and having a less number of longitudinal rows of perforations therein than the number of operating magnets.
